TABLE-RAIL SUPPORTING BRACKET

John Heaney, Brooklyn, N. Y., assignor to Treitel-
Gratz Co. Inc., New York, N. Y., a corporation
of New York

Application April 18, 1946, Serial No. 663,068

9 Claims. (Cl. 311—106)

1

My present invention relates generally to tables, and has particular reference to improvements in peripheral table-rails and to the supporting means therefor.

It is a general object of the invention to provide an improved means for conveniently and expeditiously mounting and demounting a peripheral guard rail in association with a table. Such rails are customarily employed on shipboard, and the invention is primarily intended for such use, but it will be understood that certain phases of the invention are not necessarily restricted to such a specific purpose and may be of wider utility in association with tables generally, wherever the occasional provision of a peripheral rail is deemed to be desirable or necessary.

From one aspect, my invention relates to the guard rail itself, and aims to provide a novel type of flexible resilient band which may be associated with a table in stretched condition to constitute a table-rail of unusually efficient character.

From another aspect, the invention is directed to an improved type of bracket by means of which a table-rail, especially a rail in the form of a flexible band, may be braced and supported to hold it in place.

It is a particular object of the invention to provide a bracket of special design whose construction is such that it may not only be secured to the table in a simple and convenient manner, but may also be expeditiously adjusted between an inoperative out-of-the-way disposition on the underside of the table, and an operative disposition alongside the table edge.

The improved bracket comprises an attachment element adapted to be secured to the table, and the construction is characterized by the provision of a rail-bracing arm which is pivoted to the attachment element in such a manner that it may be readily swung between the inoperative and operative positions mentioned. A feature of the invention resides in a means for releasably retaining the arm against inadvertent displacement when it is in its operative position, and in the preferred embodiment, this retaining means is associated with the pivot around whose axis the arm is adapted to swing. Another feature of the invention resides in the provision of a means for releasably latching the arm in its inoperative position beneath the table.

It is a particular feature of the invention to provide an assembly of parts which allows at least the rail-bracing arm and preferably the

2

bracket as a whole to be shifted bodily on the underside of the table toward and away from a position adjacent to the table edge, whereby the bracket may be more fully concealed from view when it is not in use, and whereby the adjustment of the bracket into its operative relation to the table edge and to the table-rail may nevertheless be swiftly accomplished whenever desired.

I achieve the foregoing general objects and 10 advantages, and such other objects and advantages as may hereinafter appear or be pointed out, in the manner illustratively exemplified in the accompanying drawings in which:

Figure 1 is a perspective view of a table-rail and bracket of the present character, shown in operative position with respect to a table edge;

Figure 2 is an enlarged cross-sectional view taken substantially along the line 2—2 of Figure 1;

Figure 3 is a view similar to Figure 2 showing the parts in an adjusted relationship;

Figure 4 is a view of the bracket of Figure 3, viewed from underneath; and

Figure 5 is a cross-sectional view taken substantially along the line 5—5 of Figure 4.

In Figures 1 and 2 I have shown an illustrative table 10 in association with a table-rail 11 intended to define an upstanding peripheral wall or guard. In accordance with one objective of the invention, the rail 11 consists of a resilient flexible elongated band of soft material, such as stretchable soft rubber or its equivalent, fitted around the table edge in a tensioned or stretched condition. At strategic spaced intervals along the edge of the table, brackets are provided for affording transverse support for the band 11. One such bracket is shown in the present drawings.

The bracket I have chosen to illustrate consists of an attachment element of U-shaped cross-section, the bottom wall 12 constituting a plate lying flat against the underside of the table. Along its opposite longitudinal edges, the plate 12 is provided with the upstanding spaced ears or flanges 13. Adjacent to the outer edge of this element, a pivot pin 14 extends transversely between the ears 13 and is journaled within these ears in any suitable fashion. Mounted on the pivot 14 is an arm 15, the articulation being at one end of the arm 15, so that the arm may swing freely about the axis of the pivot 14.

In the illustrated construction, the attachment element or plate 12 is provided with a longitudinal slot 16. This is a guide slot adapted to cooperate with at least one securing element carried by

the table and extending downwardly through the slot. I have illustratively shown two such elements in the form of headed screws 17. These screws hold the attachment element 12 to the underside of the table, and they also permit the element 12 to be shifted between the two positions indicated in Figures 2 and 3. In the first of these positions, the pivot 14 is brought into substantial alignment with the peripheral edge of the table 10. In the position of Figure 3, the pivot has been shifted rearwardly away from the table edge.

When the element 12 is shifted into the position of Figures 1 and 2, the arm 15 swings readily into the upright disposition shown, wherein it lies against the peripheral edge of the table, projecting slightly above the level of the table top, and wherein it affords transverse support for the band or rail 11. To facilitate this support, the arm 15 is provided at its free end with a projection 18 adapted to engage with the upper longitudinal edge of the band 11. The arm 15 may also be provided with the projection 19 which lies adjacent to the lower edge of the band 11. The projections 18 and 19 are of advantage in assuring a proper maintenance of the band 11 in the desired relation to the table.

When the table-rail is to be removed, its stretchability permits it to be disengaged from the supporting arm 15, and the latter may then be swung in the direction of the arrow 20 (Figures 2 and 3) through approximately 270°, as indicated in Figure 3. At the same time, the bracket as a whole may be shifted rearwardly away from the table edge, into an inconspicuous out-of-the-way position beneath the table. In the preferred construction, a keeper 21 is secured to the underside of the table by means of screws 22 or the like, and a cooperable latch is formed on the bracket for engaging with this keeper when the parts are adjusted into their inoperative condition. Preferably, the arm 15 may constitute the latch, the projection 18 serving as a convenient latching hook for engagement with the keeper 21. This assures a maintenance of the bracket in its retracted inoperative position beneath the table.

In order to retain the arm 15 in its upright position, as shown in Figure 2, independently of the band 11, I provide a special means in association with the pivot 14 for yieldably locking the arm in the position of Figure 2, against accidental displacement. This construction is most clearly shown in Figures 4 and 5, and consists of cooperable detent portions formed on the arm 15 and on the attachment element 12, a spring means being provided for yieldably pressing these portions into engagement when the arm 15 is in its operative position. More particularly, it will be observed that the articulated end of the arm 15 is provided with the enlarged hub portion 23. At one end, this hub is provided with transverse grooves 24 arranged at 90° to each other. At its opposite end, the hub is provided with a bore 25 adapted to accommodate a compression spring 26. This spring bears against the corresponding ear 13 of the attachment element 12, and serves constantly to urge the hub 23 against the opposite ear 13. The latter is provided with a pair of raised ribs 27, also arranged at right angles to each other (as shown most clearly in Figure 1), the ribs being raised on the inside surface of the ear, for cooperation with the grooves 24.

As a result of this construction, the grooves 24 snap into engagement with the ribs 27 whenever

the arm 15 is swung into its upright operative position. This serves to hold the arm in this position, although a deliberate pressure upon the arm in the direction of the arrow 20 will readily cause a release of the engagement between the detent portions. When the arm reaches the inoperative position indicated in Figure 3, the grooves 24 engage again with the ribs 27 to hold the arm 15 in the latched engagement with the keeper 21.

The construction as a whole is simple, inexpensive, compact and unusually efficient. During normal usage of the table, the brackets are all in concealed disposition beneath the table. Where the rail is of the flexible band type illustrated, 15 the band itself may be conveniently rolled or folded into a compact bundle and stored beneath the table in a suitable clip or holder. Whenever the rail is to be associated with the table edge, it is a relatively simple matter to reach beneath 20 the table, disengage each of the bracket arms, and at the same time pull the arm forwardly to the table edge and swing it upwardly into its operative position. The fact that the arm snaps readily into this position and is yieldably held 25 against accidental displacement adds to the facility with which the rail may be applied. The rail itself is then fitted in tensioned condition around the table edge, and wherever there is an upstanding bracket arm, the rail is fitted against 30 the arm as shown in Figure 1. This holds it in position and affords a staunch transverse bracing.

It will be understood that those skilled in the art may readily modify the proportions, contours and other details herein illustrated and described, 35 without necessarily departing from the spirit and scope of the invention as expressed in the appended claims.

Having thus described my invention and illustrated its use, what I claim as new and desire to 40 secure by Letters Patent is:

1. The combination with a table, of a table-rail bracket secured to the underside of the table and comprising an attachment element, an arm pivoted to said attachment element for swinging 45 movement between an inoperative position beneath the table and an operative upright rail-supporting position alongside the table edge, and means for securing said attachment element to the underside of the table in shiftable relation thereto so that the bracket may be shifted bodily 50 toward and away from the table edge when said arm is in its inoperative position.

2. The combination with a table, of a table-rail bracket secured to the underside of the table and comprising an attachment element and an arm pivoted thereto for swinging movement between an inoperative position beneath the table and an operative upright rail-supporting position alongside the table edge, and means for shifting 55 said attachment element toward and away from the table edge when said arm is in its inoperative position, said means comprising a guide slot in said element and at least one securing element carried by the table and extending downwardly 60 through said slot.

3. The combination with a table, of a table-rail bracket secured to the underside of the table and comprising an attachment element, an arm pivoted to said attachment element for swinging 65 movement between an inoperative position beneath the table and an operative upright rail-supporting position alongside the table edge, means for securing said attachment element to the underside of the table in shiftable relation thereto so that the bracket may be shifted bodily 70

75

toward and away from the table edge when said arm is in its inoperative position, and means for releasably locking said bracket in its remote position relative to the table edge.

4. The combination with a table, of a table-rail bracket secured to the underside of the table and comprising an attachment element, an arm pivoted to said attachment element for swinging movement between an inoperative position beneath the table and an operative upright rail-supporting position alongside the table edge, means for securing said attachment element to the underside of the table in shiftable relation thereto so that the bracket may be shifted bodily toward and away from the table edge when said arm is in its inoperative position, and means for releasably locking said bracket in its remote position relative to the table edge, said last-named means comprising a keeper secured to the table, and a cooperable latch carried by said bracket.

5. The combination with a table, of a table-rail bracket secured to the underside of the table and comprising an attachment element, an arm pivoted to said attachment element for swinging movement between an inoperative position beneath the table and an operative upright rail-supporting position alongside the table edge, a rail-retaining projection on said arm, means for securing said attachment element to the underside of the table in shiftable relation thereto so that the bracket may be shifted bodily toward and away from the table edge when said arm is in its inoperative position, and a keeper secured to the table and adapted to engage with said projection when the bracket is shifted to its remote position relative to the table edge.

6. In combination with a table, an attachment element secured in such manner to the underside of the table that it may be shifted to bring its outer portion forwardly toward or rearwardly away from a substantially aligned position with respect to the table edge, and an arm pivoted at one of its ends to said outer portion of said attachment element, the axis of said pivot being substantially aligned with the table edge when the attachment element is in its forward position, whereby said arm may be swung into an upright position alongside the table edge, said

arm in said upright position extending above the table top to afford transverse support for a flexible band defining a peripheral table-rail.

7. The combination with the elements set forth in claim 6, of a yieldable means associated with said pivot for retaining the arm in said upright position.

8. The combination with the elements set forth in claim 6, of a yieldable means associated with said pivot for retaining the arm in said upright position, and a means for engaging the free end of the arm beneath the table when the arm is swung downwardly and the attachment element is shifted rearwardly.

9. The combination with a table, of a table-rail bracket comprising an attachment element and an arm pivoted thereto, said attachment element being secured to the underside of the table and comprising a plate having spaced upstanding ears, said arm having one end pivotally supported between said ears and adapted to swing between an inoperative position beneath the table and an operative upright position alongside the table edge, said arm in its operative position extending

above the table top to afford transverse support for a flexible band defining a peripheral table-rail, and means for shifting said bracket bodily toward and away from the table edge when said arm is in its inoperative position.
